[57] **CLAIM**

The ornamental design for a combined melter and dispenser for thermoplastic material, as shown and described.

DESCRIPTION

FIG. 1 is a reduced perspective view of a combined melter and dispenser for thermoplastic material showing my new design;

FIG. 2 is a top view thereof;

FIG. 3 is a front view thereof;

FIG. 4 is a rear view thereof;

FIG. 5 is a side view taken from the left of FIG. 3;

FIG. 6 is a side view taken from the right of FIG. 3;

FIG. 7 is a bottom view thereof.

The flexible tubing and electrical cord are shown broken away to indicate indeterminate length.

FIG. 1

FIG. 2

FIG. 3

FIG. 4

FIG. 5FIG. 6FIG. 7
